UNITED STATES PATENT OFFICE.

JOSEPH N. MAHONEY, OF WILKINSBURG, AND WALTER M. AUSTIN, OF SWISSVALE, PENNSYLVANIA, ASSIGNORS TO WESTINGHOUSE ELECTRIC AND MANUFACTURING COMPANY, A CORPORATION OF PENNSYLVANIA.

ELECTRICAL SYSTEM.

1,363,666.

Specification of Letters Patent. Patented Dec. 28, 1920.

Application filed August 30, 1916. Serial No. 117,666.

To all whom it may concern:

Be it known that we, JOSEPH N. MAHONEY, a citizen of the United States, and a resident of Wilkinsburg, in the county of Allegheny and State of Pennsylvania, and WALTER M. AUSTIN, a citizen of the United States, and a resident of Swissvale, in the county of Allegheny and State of Pennsylvania, have invented a new and useful Improvement in Electrical Systems, of which the following specification is a continuation in part of Patent No. 1,278,967, issued Sept. 17, 1918.

Our invention relates to electrical systems and devices and particularly to means for automatically connecting feeder circuits together, under predetermined conditions.

One object of our invention is to provide a system of the above-indicated character that shall have means dependent upon the sum of the voltages of the circuits that are to be connected together for controlling the opening and closing of the connection between the same.

Another object of our invention is to provide means whereby the limiting resistance, that is connected in series with the actuating and holding windings of the connecting circuit interrupter, is adapted to be short-circuited only when the interrupter is being closed.

In the carrying out of our invention, we provide a circuit interrupter for operatively connecting two feeder circuits together and means for so controlling the interrupter that the circuits will be connected together only when the sum of the voltages on the two circuits exceeds a predetermined value. Means is also provided whereby the limiting resistor, that is connected in series with the actuating winding of the interrupter, is adapted to be short-circuited only when the interrupter is being closed. Thus, only a relatively small current traverses the actuating winding when the interrupter is in its full open and in its closed position.

Figure 1 of the accompanying drawings is a diagrammatic view of an electrical circuit embodying our invention, and Figs. 2, 3, 4, 5 and 6 are diagrammatic views of electrical circuits embodying modified forms of our invention.

Two feeder conductors 1 and 2, having a common return conductor 3, are adapted to be operatively connected together by a cir-

cuit interrupter 4 when the sum of the voltages between the feeder conductors and the common return conductor exceeds a predetermined value.

In Fig. 1 of the drawings, the circuit interrupter 4 comprises main stationary contact members 5 and 6, a main bridging contact member 7, a toggle mechanism 8, an actuating electromagnet 9, an auxiliary stationary contact member 10, an auxiliary movable contact member 11 and a limiting resistor 12. A relay 13, comprising a movable core member 14, two windings 15 and 16, a movable bridging contact member 17 and stationary contact members 18, is provided for the purpose of controlling the circuit of the actuating electromagnet 9. One terminal of the winding 15 is connected, through a resistor 19, to the feeder conductor 2, and the other terminal of the winding 15 is connected to the conductor 3. One terminal of the winding 16 is connected, through a resistor 20, to the conductor 1 and the other terminal of the winding 16 is connected to the common return conductor 3.

The windings 15 and 16 of the relay 13 are so proportioned that the movable bridging contact member will engage the stationary contact members 18 only when the sum of the voltage drops between the feeder conductors 1 and 2 and the common return conductor 3 exceeds a predetermined value. When this occurs, current is permitted to traverse the winding of the electromagnet 9, and the circuit interrupter 4 is closed. The contact members 10 and 11 constitute the separable terminals of a short-circuit connection across the terminals of the resistor 12 and are so arranged that, when the circuit interrupter 4 is closed, they are disengaged to thereby limit the current that traverses the winding of the electromagnet 9.

In Fig. 2 of the drawings, the winding of the actuating electromagnet 9 is connected in series with the limiting resistor 12 and the circuit, thus constituted, is so connected to two resistors 19 and 20 that the winding of the electromagnet 9 will be supplied with current proportional to the sum of the voltage drops across the feeder conductors 1 and 2 and the common return conductor 3. The circuit interrupter 4 is provided with an auxiliary movable contact member 11 that is adapted to engage auxiliary stationary con-

tact members 10 for the purpose of short-circuiting the resistor 12 when the circuit interrupter 4 is in its open position, thereby permitting sufficient current to traverse the 5 winding of the electromagnet 9 to actuate the circuit interrupter 4 when the sum of the voltage drops is a predetermined value.

In Fig. 3 of the drawings, one terminal of the winding of the actuating electromagnet 10 9 of the circuit interrupter 4 is connected to one terminal of the resistors 19 and 20 and its other terminal is connected to the conductor 3. The other terminals of the resistors 19 and 20 are connected to the conductors 1 and 2, respectively. With such an arrangement, the winding of the electromagnet 9 is supplied with current proportional to the sum of the voltage drops across the 15 feeder conductors 1 and 2 and the return conductor 3, but no means is provided for limiting the amount of current that traverses the winding of the electromagnet 9 when the circuit interrupter 4 is in its open or in its closed position.

20 In Fig. 4 of the drawings, one terminal of the winding of the electromagnet 9 is connected to the conductor 2 and its other terminal is connected to the stationary contact member 21 of a relay 22. One terminal of the winding 23 of the relay 22 is connected to one terminal of each of the resistors 19 and 20, the other terminals of which are connected to the conductors 1 and 2, respectively. The other terminal of the winding 25 23 is connected to a stationary contact member 24 and also to the common return conductor 3. The stationary contact members 21 and 24 of the relay 22 are adapted to be bridged by a movable contact member 25 when the sum of the voltage drops across the 30 feeder conductors 1 and 2 and the return conductor 3 exceeds a predetermined value. Thus, the winding of the electromagnet 9 will be supplied with energy only when the 35 relay 22 is closed.

Since it is advisable to limit the current in the actuating winding of the circuit interrupter when the circuit interrupter is in its open and closed positions and to permit a 40 maximum current to traverse the winding only when the interrupter is being closed, we provide the circuit interrupter 4, as shown in Fig. 5 of the drawings, with two auxiliary movable contact members 26 and 50 27 that are adapted to engage stationary contact members 28 and 29 and 30 and 31, respectively. The actuating electromagnet 9 comprises two windings 32 and 33. One terminal of the winding 33 is connected to the conductor 2 and the other terminal of the winding 33 is connected to one terminal of a resistor 34. One terminal of the winding 32 is connected to the conductor 1 and the other terminal of the winding 32 is connected to 55 one terminal of a resistor 35. The other ter-

minals of the resistors 34 and 35 are connected together and to the stationary contact member 36 of a relay 37. The stationary contact member 36 is also connected to one terminal of the winding 38 of the relay 37 70 the other terminal of which is connected to the conductor 3. The stationary contact member 31 of the circuit interrupter 4 is connected to the stationary contact member 39 of the relay 37 and the stationary contact member 28 of the circuit interrupter 4 is connected to the stationary contact member 40 of the relay 37. The stationary contact members 29 and 30 of the circuit interrupter 4 are connected to one terminal of the windings 32 and 33, respectively. The relay 37 is provided with a bridging contact member 41 that is adapted to engage the stationary contact members 36, 39 and 40 when the sum of the voltage drops across the feeder conductors 1 and 2 and the return conductor 3 exceeds a predetermined value.

As shown in Fig. 5 of the drawings, when the sum of the voltages is below a predetermined value, the windings 32 and 33 will not 90 be sufficiently energized to hold the main contact members of the circuit interrupter 4 in their closed positions, and the resistors 31 and 35 will be connected in circuit with the respective windings of the actuating electromagnet 9. However, when the interrupter 4 is open, the bridging contact members 26 and 27 engage their respective stationary contact members in such manner that, when the relay 37 is again actuated, the resistors 100 34 and 35 will be short-circuited, and sufficient current will be permitted to traverse the windings 32 and 33 to close the interrupter 4. When the interrupter 4 is closed, the bridging contact members 26 and 27 are 105 disengaged from their respective stationary contact members, and the short-circuit connections across the terminals of the resistors 34 and 35 are opened, thereby reducing the current that traverses the windings 32 110 and 33.

In Fig. 6 of the drawings, the electromagnet 9 is provided with a single winding, one terminal of which is connected to one terminal of the winding 42 of the relay 43 115 and the other terminal of the relay is connected to the conductor 3. The relay 43 is adapted to cause its movable bridging contact member 44 to engage its stationary contact members 45 for effecting a short-circuit 120 connection around the terminals of the resistor 12 only when the interrupter 4 is open and the sum of the voltage drops across the feeder conductors 1 and 2 and the return conductor 3 exceeds a predetermined value. 125 The interrupter 4 is provided with an auxiliary bridging contact member 11 and auxiliary stationary contact members 10 for opening the short-circuit connection as soon as the interrupter is closed, thereby reducing 130.

the current that traverses the winding of the electromagnet 9 when the interrupter is in its closed position.

We do not limit our invention to the particular structures and arrangements illustrated, as it may be variously modified within the spirit and scope of the appended claims.

We claim as our invention:

- 10 1. In a system of distribution, the combination with two feeder conductors, a common return conductor, and a circuit interrupter for operatively connecting the feeder conductors together, of means actuated under all conditions, in accordance with the sum of the voltage drops between the respective feeder conductors and the return conductor for controlling the opening and closing of the circuit interrupter.
- 20 2. In a system of distribution, the combination with a circuit interrupter and an actuating electromagnet therefor, of a resistor, and means for so controlling the effectiveness of the resistor in the circuit that it limits the current traversing the electromagnet only when the interrupter is in its full-open and in its closed position.
- 30 3. In a system of distribution, the combination with a circuit interrupter, an actuating and holding electromagnet therefor and a resistor operatively connected in circuit with the said electromagnet, of means for short-circuiting the resistor only when the circuit interrupter is being closed.
- 35 4. The combination with two feeder conductors, a common return conductor, and a circuit interrupter for connecting the feeder conductors together, of an actuating electromagnet responsive, under all conditions, to the sum of the voltage drops between the feeder conductors and the return conductor for controlling the operation of the interrupter.
- 45 5. In a system of distribution, the combination with two feeder conductors, a common return conductor, and a circuit interrupter for operatively connecting the two feeder conductors together, of means for closing the interrupter and for holding it in its closed position, and means responsive, under all conditions, to the sum of the voltage drops between the two feeder conductors

and the common return conductor for controlling the operation of the said closing and holding means.

6. In a system of distribution, the combination with two feeder conductors, a common return conductor, and a circuit interrupter operatively connecting the two feeder conductors together, of electromagnetic means for closing and holding the interrupter in its closed position, and means responsive, under all conditions, to the sum of the voltage drops across the two feeder conductors and the return conductor for so controlling the operation of the electromagnetic means that the interrupter will be held in its closed position only when the sum of the voltage drops exceeds a predetermined value.

7. In a system of distribution, the combination with two feeder conductors and a common return conductor, of a circuit interrupter responsive, under all conditions, to the sum of the voltage drops across the two feeder conductors and the return conductor for operatively connecting the feeder conductors together, under predetermined conditions.

8. In a system of distribution, the combination with two feeder circuits, of means responsive, under all conditions, to the sum of the voltage drops across the two circuits for operatively connecting the circuits together only when the sum of the voltage drops exceeds a predetermined value.

9. In a circuit interrupter, the combination with an actuating electromagnet and a resistor for reducing the current traversing the same, of means for short-circuiting the resistor only when the interrupter is being closed.

10. In a circuit interrupter, the combination with an actuating electromagnet and a resistor normally connected in series therewith, of means for obliterating the limiting effect of the resistor on the electromagnet only when the interrupter is being actuated.

In testimony whereof we have hereunto subscribed our names this 22nd day of Aug., 1916.

JOSEPH N. MAHONEY.
